UNITED STATES PATENT OFFICE

JAQUES MAISCH, OF NEW YORK, N. Y.

DESIGN FOR A TEXTILE FABRIC OR THE LIKE

Application filed November 10, 1932. Serial No. 45,863. Term of patent 3½ years.

To all whom it may concern:

Be it known that I, JAQUES MAISCH, a citizen of France, residing at 1 West 67th Street, in the borough of Manhattan, city of New York, county of New York, and State of New York, have invented a new, original, and ornamental Design for a Textile Fabric or the like, of which the following is a specification, reference being had to the accompanying drawing, forming part thereof:

The dot and dash lines on the drawing outline the design unit, which unit is repeated in regular succession, as indicated by the extensions beyond the unit boundaries.

I claim:

The ornamental design for textile fabric or the like, as shown and described.

JAQUES MAISCH.
